UNITED STATES PATENT OFFICE

EMMETT ADDISON DUNLAP, OF FORT WORTH, TEXAS, ASSIGNOR TO RELIANCE MACHINE & STAMPING WORKS, INC., OF NEW ORLEANS, LOUISIANA, A CORPORATION OF LOUISIANA

PRESSURE GREASE GUN

Application filed June 10, 1930. Serial No. 460,182.

This invention relates to pressure grease guns and has for its general object the provision of a gun particularly adapted for the pressure feeding of sticks of hard grease.

One of the more specific objects of the invention is to provide a grease gun of the type described in which the plunger operating parts are carried solely by the plunger free from any mechanical connection with any other part of the grease gun so that the said parts are completely removable with the plunger, giving unimpeded access to the barrel for putting in a fresh stick of grease and also making it conveniently feasible to attach the barrel to the part to be oiled before associating with it the plunger and its appurtenant actuating mechanism.

Another object of the invention is the provision of operating mechanism which can be freely oriented around the gun barrel so as to bring the operating handle to the most convenient position.

Still another object of the invention is to provide the grease gun with a quick attachable elbow coupling to permit its operation in positions 90° displaced.

Other objects of the invention will appear as the following description of a preferred and practical embodiment thereof proceeds.

In the drawings in which the same characters of reference are used throughout the several figures to denote identical parts:

Figure 1 is a side elevation partly in section of my improved grease gun;

Figure 2 is a section taken along the line 2—2 of Figure 1, looking up;

Figures 3, 4 and 5 are consecutively, side sectional, top sectional and bottom plan views of the elbow attachment;

Figure 6 is a side elevation of a portion of a locomotive showing the grease gun applied to a nipple vertically without the elbow attachment and

Figure 7 is a similar view showing the grease gun applied horizontally with the aid of the elbow attachment, the latter in this instance being unitary with the barrel; and

Figure 8 is a longitudinal sectional view through the nipple.

Referring now in detail to the several fig-

ures and first advertiring to Figures 1 and 2, the numeral 1 represents the barrel of the grease gun which is preferably enlarged at its lower end to form a socket 2, the latter being preferably internally threaded to receive a bushing 3 formed with bayonet slots 4 and constituting a quick attachable coupling in connection with the pin 5, Figure 6, forming part of the lubricating nipple.

The barrel is formed with a bore 6 of a uniform diameter adapted to receive a stick of hard grease 7 which is to be followed by a plunger 8. The barrel is provided with a handle 9 by means of which it may be rotated through a sufficient angle to properly engage the bayonet slots 4 with the pin 5. The outer surface of the barrel is formed with a series of annular ratchet-like shoulders 10 having their abrupt faces in planes substantially perpendicular to the axis of the plunger and facing downwardly, that is to say, in the direction in which the plunger is to be forced in discharging the grease.

The operating means for the plunger comprises a handle 11 mounted upon a horizontal pivot 12 at the top of the plunger.

A pair of links 13 are arranged in parallel spaced relation at the opposite end of the handle 11 being pivotally mounted to the latter at 14. The lower ends of said links are pivotally connected at 15 to a ring pawl 16. Said ring pawl has a substantially cylindrical opening through which the barrel of the gun may freely and slidably extend when the ring is so positioned that the axis of its opening is parallel to the axis of the plunger. But when the ring pawl 16 is canted as shown in full lines in Figure 1, it binds against the sides of the barrel, the upper edge portion 17 of said ring pawl engaging beneath one of the shoulders 10 of the barrel and fulcruming there against while at the same time the opposite wall of the opening is forced against the side of the barrel, preventing relative longitudinal movement between said ring pawl and said barrel.

In operation, a stick of grease having been inserted in the barrel, the plunger together with the operating mechanism is put in place, the ring pawl which already surrounds the

lower portion of the plunger being slipped over the barrel, and the plunger being inserted within the barrel and permitted to rest against the stick of grease. The ring pawl

5 16 is then canted so that the edge portion 17 engages a shoulder as previously described, and the handle 11 is pushed downward.

This causes an upward pull upon the links 13 and creates an upward pressure between 10 the edge portion of the ring pawl and the shoulder 10 of the barrel and at the same time forces the opposite wall of the ring pawl into contact with the opposite side of the barrel. The ring pawl thus becomes im- 15 movably fixed for the moment relative to the barrel and inhibits all further upward movement of the links 13 so that the pivot 14 becomes the fulcrum for the handle 11 and downward pressure upon said handle forces 20 the plunger 8 into the barrel against the stick of grease discharging some of the latter into the fitting to which the barrel is attached.

If another shot of grease is desired, the 25 lever 11 is raised lowering the links 13, reducing the degree of cant of the ring pawl 16, permitting the latter to slip over the ratchet-like shoulder of the barrel until the edge portion 17 comes beneath another one 30 of the shoulders 10. The amount of grease to be discharged may be determined at will by taking a long or short stroke of the handle 11, causing the edge portion 17 to slip over one or more than one of the shoulders 35 at a time.

It is noted that the fitting is without a spring for assisting in seating the check valve since the stiffness of the lubricant precludes the practical functioning of a return spring.

40 Each time the lever 11 is pressed downward, the edge portion 17 of the ring pawl will be brought and held against the shoulder which it immediately underlies. This operation may be repeated until the fitting 45 has been supplied or until the stick of grease has become exhausted. The ring pawl 16 may then be restored to a position of axial parallelism with the barrel 1 and readily slid toward the upper end of the barrel simultaneously with the removal of the plunger.

50 It is also possible, as will be presently described, to elevate the plunger step by step, for removal of the latter or to reduce pressure on the grease stick so that the quick detachable coupling can be disconnected by canting the ring pawl in the opposite direction so that upon operating the handle the ring pawl presses against the shoulder below it.

55 60 There are two ways in which the ring pawl 16 may be initially canted or restored to its position of axial parallelism. One way is by mere manipulation of the finger piece 18, the latter being pushed down in order 65 to cant the ring pawl and bind it against the

barrel and pushed up in order to bring the ring pawl to a position in which it is freely slideable with respect to the barrel. The other way, and which is to be preferred, is to provide a spring pressed detent 19 which may be conveniently located between the links, said detent comprising a notched head, the notch of which is capable of being engaged with a projection 20 formed on the ring pawl, or which projection may alternatively engage one or the other of the sloping faces 21 and 22 by which the detent is flanked.

70 The detent is bolt-like in form as indicated at 23, and slides in nut-like fittings 24 and 25 pivotally secured between the links 13. The spring 26 keeps the detent in yielding engagement with the ring pawl.

75 In operating the grease gun with the detent, the finger piece 18 is manipulated to bring the projection 20 into the notch of the detent. In this position the ring pawl is retained with its axis parallel to that of the barrel and may be freely slid up and down the barrel or taken off therefrom with the plunger. When the plunger is re-inserted, the ring pawl retains this neutral position, but upon the handle 11 being depressed, the edge portion 17 bears sufficiently against the adjacent side of the barrel to cause projection 20 to spring out of the detent as shown 80 in Figure 1, canting the ring pawl so that the edge portion 17 then engages the shoulder 10 in the manner as previously described.

85 90 95 If the plunger becomes stuck in the barrel and therefore difficult to remove by mere manual pulling of the same, it may be readily removed by canting the ring pawl 16 in the opposite direction, by manipulation of the finger piece 18, so that the edge portion surrounding the opening on the right-hand side engages beneath the shoulder 10, and holding the ring pawl in this position while the handle 11 is manipulated from time to time. As the plunger is withdrawn step by step the ring pawl may be released and re-engaged upon the shoulder 10 next higher up.

100 105 110 Figure 6 shows the grease gun operating with its plunger in axial alignment with the fitting to which it is attached. This is not always a convenient position for the grease gun and consequently, the elbow fitting shown in Figure 3 is provided, the lower end of which is identical with the socket 2 shown in Figure 1 and the opposite end of which is formed with a quick attachable nipple 27 adapted to be received within the socket 2 of the grease gun. The use of this attachment is obvious and it permits the grease gun to be operated with the axis of its barrel at an angle of 90° to the axis of the fitting 115 being lubricated.

120 125 130 It is obvious that screw threads or other equivalent means could be substituted for the quick attachable means as shown, between the elbow and barrel, so that the elbow could

be carried unitarily with the barrel, as a part thereof, as indicated in Figure 7.

It will be understood that since none of the plunger mechanism is mechanically connected to the barrel, the plunger may be rotated within the barrel, carrying with it the operating mechanism and thus the handle 11 may be with the greatest of ease oriented to that position most convenient for its operation.

10 While I have in the above description endeavored to disclose what I believe to be a preferred and practical form of my invention, it is to be understood that it is merely 15 illustrative of an inventive concept and that the details of construction as shown are merely by way of example and not to be considered limitative in their bearing upon the scope of the invention as claimed.

20 What I claim is:

1. Grease gun comprising a barrel and plunger operating means including a lever pivotally connected to said plunger operating means, a ring pawl freely slideable longitudinally on said barrel and a link pivotally connecting said lever and ring pawl, the latter being inclinably in either direction relative to a plane perpendicular to the axis of said barrel so as to engage the sides of said barrel and act as a shiftable fulcrum for said lever.

2. Grease gun comprising a barrel circumferentially corrugated, a plunger reciprocable in said barrel operating means connected solely to said plunger and including an inclinable ring pawl surrounding said barrel and freely slideable thereupon adapted when inclined to engage the corrugations of said barrel to form a fulcrum for said operating means.

3. Grease gun comprising a barrel, the outer surface of which is provided with a series of circumferential shoulders, a plunger reciprocable in said barrel and operating means connected solely to said plunger including a lever pivotally connected to said plunger, a ring pawl surrounding said barrel and freely slideable longitudinally thereof, and a link pivotally connecting said lever and ring pawl the latter being inclinably in either direction with respect to a plane perpendicular to the axis of said barrel to progressively engage the shoulders thereof for affording a shifting fulcrum for said lever.

4. Grease gun as claimed in claim 3, said link including a detent for holding said ring pawl in either of its inclined positions or in a plane perpendicular to the axis of said barrel.

5. Grease gun as claimed in claim 3, the ring pawl being provided with a finger piece for changing its direction of inclination.

6. Grease gun comprising a barrel circumferentially corrugated, a plunger reciprocable in said barrel, operating means for said

plunger including an inclinable ring pawl surrounding said barrel, and a spring detent for said ring pawl for holding it inclined in either direction in engagement with said barrel or in a plane perpendicular to the axis of said barrel in which plane the ring pawl is freely slideable.

7. Grease gun as claimed in claim 6, the nozzle end being valveless.

8. In a grease gun, in combination, a cylinder having a series of projections thereon, a piston working in said cylinder, a lever pivoted to said piston and a link connected to the end of said lever and having an eye portion surrounding said cylinder and cooperating with said projections to give a step-by-step movement by said piston upon manipulation of said lever.

9. A grease gun comprising in combination, a cylinder having a series of lugs located on the body portion thereof, a pawl cooperating with said lugs, a piston, and a lever attached to said piston and pawl and operative in combination therewith to give a step-by-step movement to said piston.

10. In a grease gun, in combination, a cylinder having a series of projections thereon, a piston working in said cylinder, a lever pivoted to said piston, a ring surrounding said cylinder, a link connecting said lever and said ring, said ring cooperating with said projections to give a step-by-step movement of said piston upon manipulation of said lever.

11. In a grease gun, in combination, a cylinder having a series of projections thereon, a piston working in said cylinder, a lever pivoting on said piston rod, a ring surrounding said cylinder and cooperating with said projections and means connecting said ring and said lever.

12. Pressure grease gun comprising a barrel and a plunger unit removable as a whole from said barrel, said unit including a plunger, a handle pivoted thereto, a ring pawl surrounding said barrel and said plunger, adapted to ratchet against said barrel in the operation of the grease gun, means suspending said ring pawl from said handle, and means on said pawl engaging its suspending means to prevent its dropping below the end of said plunger when the latter is removed from said barrel.

In testimony whereof I affix my signature.
EMMETT ADDISON DUNLAP.
